[57] **CLAIM**

The ornamental design for a stackable tray for paper stock and drawings, as shown and described.

DESCRIPTION

FIG. 1 is a front perspective view of the stackable tray for paper stock and drawings showing the design of our invention;

FIG. 2 is a bottom view thereof;

FIG. 3 is a top view thereof;

FIG. 4 is a front elevation view thereof showing a like tray in reverse orientation stacked thereon in phantom; FIG. 5 is a rear elevation view thereof showing a like tray in reverse orientation stacked thereon in phantom; FIG. 6 is a right side elevation view thereof showing a like tray in reverse orientation stacked thereon in phantom;

FIG. 7 is a left side elevation view thereof showing a like tray in reverse orientation stacked thereon in phantom; and,

FIG. 8 is a bottom view of an alternate embodiment of the stackable tray of this invention, that alternate embodiment being in other respects visually the same as the embodiment shown in FIGS. 1 and 3-7.

The stackable tray depicted by means of broken lines in FIGS. 4, 5, 6 and 7 has been shown for illustrative purposes only and forms no part of the claimed design.
